UNITED STATES PATENT OFFICE.

WILLIAM L. LUKENS AND NEVIL GREENWELL, OF BETHLEHEM, PENNSYLVANIA, AS
SIGNORS TO BETHLEHEM STEEL COMPANY.

DETONATING FUSE.

Application filed October 20, 1925. Serial No. 63,594.

The present invention relates to artillery ammunition and particularly to explosive projectiles having point percussion fuses of the adjustable type.

Heretofore, it has been customary with projectile fuses of the aforesaid type to provide a single percussion firing mechanism adapted to function at impact for producing a flash or flame to ignite the detonating element of the projectile. In such prior construction, there has been interposed between the mechanism and the detonating element a delay pellet consisting of a slow burning powder, the purpose of which is to retard the progress of the flame and to cause an interval of time to elapse after impact, whereby the projectile may penetrate or pass beyond the target before exploding. A normally closed duct has been provided to by-pass the delay pellet; and, when it is desired to explode the projectile instantaneously at impact, this duct is opened previously to firing of the projectile to permit the flame to be transmitted directly to the detonating element.

In modern artillery practice, a firing mechanism which is suitable for a non-delay action type of fuse is not necessarily suitable for a fuse of the delay action type and it is preferable to have a specific form of firing mechanism for each type of fuse. For example, in the case of a projectile which is required to explode at the surface of the ground, it is preferable to provide a firing mechanism of the direct impact type. Then again, when it is desired to explode the projectile after it has penetrated or passed beyond the target, or after it has struck the ground at a small angle of incidence so that it ricochets and explodes above the ground, then a mechanism of the inertia type is preferred.

The object of the present invention is to provide a fuse for projectiles of the delay and non-delay action type having two independent percussion firing mechanisms, each of which functions at impact to initiate detonation of the projectile, one of said mechanisms constituting the non-delay action element serving to ignite the detonating charge at the instant of impact, and the other of said mechanisms constituting the delay action element serving to ignite said charge when the projectile is beyond the point of impact, and means to control the action of the fuse.

The structure made in accordance with our invention comprises generally a fuse of the

delay and non-delay action type for use with a projectile having a firing mechanism at its forward end adapted to cause the instantaneous detonation of the projectile at impact and a second firing mechanism, positioned rearwardly of the first mentioned firing mechanism, adapted to cause the detonator of the projectile after it has passed beyond the point of impact; and there is further provided a member mounted in the fuse body adapted to control the action of the first mentioned firing mechanism which is adjustable exteriorly of the fuse.

The novel features will be more fully understood from the following description and claims taken with the drawings, in which:

Fig. 1 is a longitudinal cross section of a detonating fuse illustrating an embodiment of the invention and shows the fuse in its safe or unarmed condition and set for instantaneous or non-delay action;

Fig. 2 is a cross section taken on line II--II of Fig. 1 and shows the control member set for non-delay action;

Fig. 3 is a similar view to that shown in Fig. 2 with the control member set for delay action;

Fig. 4 is a partial cross section similar to Fig. 1 illustrating the position assumed by the parts of the instantaneous firing mechanism at the firing of the projectile from the gun;

Fig. 5 is a cross section taken on line V--V of Fig. 1, and shows the detonating element in its safe position;

Fig. 6 is a cross section taken on line VI--VI of Fig. 1;

Fig. 7 is a cross section similar to Fig. 1 illustrating the position of the parts at the point of impact;

Fig. 8 is a cross section taken on line VIII--VIII of Fig. 7 and is similar to Fig. 5 and shows the detonating element in its armed position;

Fig. 9 is a fragmentary side elevation of the fuse illustrating an end view of the control member in the position shown in Fig. 3; and

Fig. 10 is a fragmentary side elevation of the fuse illustrating an end view of the control member in the position shown in Fig. 2.

Referring to the drawings, 10 indicates the projectile body threaded internally at 11 to receive a fuse body 12. The fuse body is preferably made of two parts to facilitate assem-

bly of the firing mechanism, it comprising the head portion 13 and a rear portion 14 in threaded engagement, as at 15, and in axial alignment with each other.

5 The head portion is provided at the forward end with an axial cylindrical recess 16, in which is slidably contained a striker member 17 and a primer holder 18. The latter member is of hollow construction, and the 10 striker member 17 is slidably mounted therein.

Within the holder 18 is disposed a movable percussion primer 19, which is normally held apart from the striker 17 by a coil spring 20. 15 The holder 18 is connected with the fuse body by a pin 21 which is intended to be sheared when the projectile is discharged from the gun.

The striker 17 is connected to the fuse body 20 by a pin 22 which is of sufficient strength to oppose the stresses imposed thereon by the inertia of the striker due to the shock of discharge, but, however, is intended to be sheared off at the impact of the projectile 25 with a target.

The striker is provided with an elongated opening 23 to allow the passage of the pin 21 without interfering with the rearward movement of the holder relative to the striker.

30 It is preferable that the primer be maintained positively in spaced relation to the striker and not to depend solely upon the spring 20 to prevent the premature firing of the primer when handling or transporting the 35 projectile. To this end, I provide a perforated disc 24 loosely mounted in the holder and interposed between the spring and the primer. Tenons 25 extend laterally from the disc 24 and project through elongated openings 26 formed in the holder and beyond the exterior surface of the latter to engage a fixed shoulder 27 of the fuse body. In order to 40 permit the holder to be assembled in position, the fuse body is provided with slots 27' to allow for the passage of the tenons 25.

The above described parts constitute the instantaneous firing mechanism of the fuse which operates in the following manner: When the projectile is fired from a gun, 50 inertia of the holder 18 and its associated parts will cause the pin 21 to shear and the holder will move rearwardly, relatively to the body until limited by the forward face of the shoulder 27 engaging the shoulder 18' on the 55 holder whereupon the holder occupies the position illustrated in Fig. 4. The pin 22 resists the action of inertia of the striker during the acceleration of the projectile and the striker remains in its normal position during 60 the flight of the projectile. As explained above, the primer 19 and the disc 24 are freely mounted in the holder 18; and, due to the deceleration of the projectile, these parts creep towards their original position where the lugs 65 25 come close to or engage the shoulder 27.

When the projectile strikes the target the striker 17 will be forced rearwardly, shearing the pin 22, and the needle portion 28 will fire the primer 19, which during the impact period is maintained in its forward position due to 70 its inertia.

Assuming that the pin 22 inadvertently shears upon shock of discharge of the projectile from the gun and thus allows the premature rearward movement of the striker, 75 danger of contact of the needle 28 with the primer 19 is prevented by the shoulder 29 formed on the striker abutting the forward face 30 of the holder 18. Thus it will be seen that, if both pins 21 and 22 shear due to a 80 shock imposed upon the parts tending to cause their simultaneous rearward movement, a premature contact between the needle and the primer would not occur. Assuming that pin 22 should shear, due to some unforeseen accident, which did not affect the pin 21, and the striker should move rearwardly toward the primer, such movement would be limited by the shoulder 29 abutting the forward face 30 of the holder 18. From the foregoing description, it will be seen that we have provided a sensitive direct action firing mechanism which is simple in construction and safe under various conditions arising in handling and transportation. 90

Referring to the delay action firing mechanism and also to the safety device, which we provide for carrying the detonating element, such mechanisms are preferably of the type shown and described in application Serial No. 100 563,475, filed May 25, 1922, and assigned to the Bethlehem Steel Company.

The head portion 13 is provided with an axial recess 31, in which is slidably mounted an inertia, percussion plunger 32 having a 105 longitudinal groove 33 formed in the exterior surface thereof engaging a pin 34 fixed to the fuse body to prevent the relative rotation of the plunger with respect to said body. The recess 31 communicates with the recess 110 16 by means of the duct 35.

Radially disposed centrifugally operating bolts 36 normally prevent forward movement of the plunger 32. The latter is supported rearwardly by the perforated diaphragm 37, 115 which is clamped between the rear end head portion of the fuse body and the bottom of the recess in the base portion 14 and which constitutes a closure for the plunger recess 31. The aperture 38 in the diaphragm 37 permits 120 passage of the flame to the detonating element as hereinafter described.

The plunger 32 is provided with a recess 32 disposed eccentrically with reference to the axis of the fuse body and parallel thereto, the recess having portions of suitable sizes for the primer 39, the delay pellet 40 composed of any suitable slow burning powder, and the flash charge adapted to augment the flame from the delay pellet after the latter has burned a 130

predetermined interval of time. A firing pin 41 is fixed to the fuse body and extends into the plunger recess 31 and it is disposed in alignment with the primer 39.

5 When the fuse is unarmed, the primer 39 and the firing pin 41 are maintained in spaced relation by the bolts 36. To prevent the plunger from creeping towards the firing pin 41 during the flight of the projectile, a coil spring 42 is provided and it is positioned between the shoulder 43 formed on the plunger and the shoulder 44 formed on the fuse body.

10 To permit the passage of the flame from the primer 19 to the detonator in the manner hereinafter described, an axial opening 45 is provided in the plunger 32.

The rear portion 14 of the body is provided with a recess 46 formed eccentrically of the fuse body and which contains a rotor 47 of irregular form mounted on the pivot 48. The rotor is recessed to receive a detonator 49 and it is also provided with a radially-disposed recess in which is slidably mounted a pin 50 responsive to centrifugal force to enter a recess 51 in the body and thereby locks the rotor in armed position. Oscillation of the rotor is limited by a pin 52 projecting inwardly from the body and in a position to engage the shoulder 53 formed on the rotor.

20 The position of the detonator 49 relative to the pivot 48 is such that when the rotor 47 is oscillated into the armed position, the detonator is in alignment with the opening 45 in the plunger 32, as shown in Figs. 7 and 8, and in the direct passage of the flame from the firing mechanism.

The rotor 47 is normally held against oscillation by centrifugally operated bolts 54, slidably mounted in radially-disposed pockets formed in the body and which engage the shoulders 55 formed on the rotor. When the rotor is in the latter position the detonator 49 is not in alignment with the aperture 38, as shown in Figs. 1 and 5, and the flame from the firing mechanism would not cause the explosion of the detonator. Furthermore, the detonator, if exploded in this position, would not be effective to explode the booster charge hereinafter mentioned.

25 The rear end of the body is provided with a cavity 56, which is in communication with the recess 46 through the passage 57. The cavity 56 and passage 57 contains a booster charge of any suitable composition. The rear end of the cavity 56 is closed by means of the disc 58 which is crimped in a recess formed in the body, and in conjunction with the cap 59 confines the booster charge within the cavity 56 and passage 57.

30 A laterally disposed opening 60 is formed in the fuse body and it intersects the duct 35. A portion of the opening 60 is tapered to constitute a seat for the tapered cock 61, which is rotatably mounted in the fuse body. The cock 61 is urged to its seat by the coil spring

62, whose outer end abuts the threaded plug 63. A diametral aperture 64 is formed in the cock for permitting free passage of the flame from the primer 19 through the duct 35.

When the cock or valve 61 is turned substantially 90° from the position shown in Fig. 1 to the position shown in Fig. 3, a kerf 65 being provided at the small end of the cock or valve in order that it may be turned by any suitable tool, the duct 35 is blocked; and, in this position of the cock or valve, a port 66 in the head 12 registers with a port 67 in the valve or cock, the latter bolt being arranged to discharge axially of the valve or cock and the plug 63 being provided with a vent opening or aperture 68. With the cock or valve in this position, therefore, the flame from the primer will be vented through the ports 66, 67 and 68 to the atmosphere.

35 Suitable marking is provided on the exterior surface of the fuse body, as at 69, and in conjunction with the arrow 70 engraved or stamped at the end of the cock indicates the position of the aperture 64 relative to the duct 35. In Fig. 9, the arrow points in the direction of "D" and indicates that the fuse is set for delay action, that is, the cock closes the duct 35. When the cock is rotated to the position shown in Fig. 10, that is, when the arrow points in the direction of "N. D", it indicates that the fuse is set for instantaneous or non-delay action and in this position the aperture 64 is in registry with the duct 35 to permit the free passage of the flame to the detonator. Normally it is adjusted for instantaneous action as shown in Fig. 1.

40 At the moment of firing, the pin 21 is sheared due to the inertia of the holder 18. With the cessation of acceleration and during the flight of the projectile, the bolts 54 fly outwardly and the rotor 47 oscillates, under the influence of centrifugal force due to the rotation of the projectile, and thus positions the detonator 49 in registry with the aperture 38 and passage 51. The bolts 36 also move outwardly beyond the path of the plunger 32 and the fuse is in its armed condition, as shown in Fig. 7. At impact the striker 17 is forced rearwardly, shears the pin 22, and fires the primer 19. The flame thus produced passes through the duct 35, opening 45 and aperture 38 to the detonator 49 which functions in turn to explode the booster charge through the passage 57. In this manner, the projectile is exploded almost instantaneously upon direct impact with the target.

45 When it is desired to use the fuse as a delay action fuse, the cock 61 is rotated through a movement of 90° into a position to close the duct 35 and allow for the flame from the primer 19 to be vented to the atmosphere, as shown in Fig. 3, to prevent such flame from causing the instantaneous explo-

sion of the projectile. At impact the plunger 32 moves forward relatively to the fuse body and the firing pin 41 fires the primer 39 and ignites the delay pellet 40 which, in turn, 5 flashes through the aperture 38 causing the detonation of the detonator 49 which functions to explode the projectile.

From the foregoing, it will be seen that we have devised a simple and novel fuse construction of the delay and non-delay action type having a specific form of firing mechanism for each action which may be controlled by the gunner according to the characteristics of the target.

15 While we have shown our invention in but one form, it will be obvious to those skilled in the art that it is not so limited, but is susceptible of various other changes and modifications without departing from the 20 spirit thereof, and we desire, therefore, that only such limitations shall be placed thereupon as are imposed by the prior art or as are specifically set forth in the appended claims.

25 Having thus described our invention, what we claim as new and desire to secure by Letters Patent is:

1. In a fuse, the combination of a fuse body, 30 a detonating element, a firing mechanism mounted in the fuse body, a duct formed in said body to transmit the flame from said firing mechanism to the detonating element, a valve member rotatably mounted in said body and having an aperture therein whereby said duct is open in one position of said member and closed in another position of said member, and a passageway formed in said valve member for venting the flame from said firing mechanism to the atmosphere when the 40 duct is closed.

2. In a percussion fuse, the combination of 45 a fuse body, a striker slidably mounted in said body and normally secured thereto, a holder slidably mounted in said body and normally secured thereto, a primer slidably mounted in said holder in alignment with said striker, and a means for preventing the forward movement of the primer from its normal position towards the striker.

50 3. In a percussion fuse, the combination of a fuse body, a striker mounted in said body, frangible means securing said striker to said body, a holder coaxial with the striker, a second frangible means securing said holder to said body, a primer slidably mounted in said holder, and means to normally prevent the forward movement of the primer.

55 4. In a percussion fuse for projectiles, the

combination of a fuse body, a striker mounted in said body, frangible means securing said striker to said body adapted to rupture at impact, a holder mounted in the fuse body, a second frangible means securing said holder to said body adapted to rupture during the acceleration of the projectile, a primer slidably mounted in said holder in alignment with said striker, and means to normally prevent the forward movement of the primer.

5. In a percussion fuse for projectiles, the combination of a fuse body, a detonating element, a striker mounted in said body, frangible means securing said striker to said body adapted to rupture at impact, a holder mounted in the fuse body, a second frangible means securing said holder to said body adapted to rupture during the acceleration of the projectile, a primer slidably mounted in said holder in alignment with said striker, means to normally prevent the forward movement of the primer, a duct formed in said body communicating said primer with said detonating element, and a member rotatably mounted in said body adapted to interrupt said communication.

6. In a percussion fuse for projectiles, the combination of a fuse body, a detonating element, a striker mounted in the forward end of said body, frangible means securing said striker to said body adapted to rupture at impact, a holder mounted in the fuse body, a second frangible means securing said holder to said body adapted to rupture during the acceleration of the projectile, a primer slidably mounted in said holder in alignment with said striker, means to normally prevent the forward movement of the primer, a duct formed in said body communicating said primer with said detonating element, an apertured plunger slidably mounted in said body, a delay primer carried by said plunger, a firing pin fixed to said body in alignment with said delay primer, the aperture in said plunger being aligned with said duct, means mounted in said body to normally prevent the movement of said plunger, a passageway formed in said body communicating said delay primer with said detonating element, and a member rotatably mounted in said body intersecting said duct and having an opening therein.

In testimony whereof I hereunto affix my signature this 10th day of Oct. 1925.

WILLIAM L. LUKENS.

In testimony whereof I hereunto affix my signature this tenth day of October 1925.

NEVIL GREENWELL.
